CLAIM

The ornamental design for an electronic bath control, as shown and described.

DESCRIPTION

FIG. 1 is a perspective view of an electronic bath control showing my new design;

FIG. 2 is a front elevational view thereof;

FIG. 3 is a left side elevational view thereof, the right side view being a mirror image of the left side; and,

FIG. 4 is a top plan view thereof.

1 Claim, 4 Drawing Sheets**FIG. 1**

FIG. 2

FIG. 3

FIG. 4
